Technical drawing of a mechanical device, labeled Fig. 1, showing various components and numbered parts. The drawing includes a top view of a rectangular frame with internal mechanisms. Key labeled parts include:

- 38: A vertical rod or lever on the left.
- 110: A rectangular component near the top left.
- 41: A small rectangular component near the center.
- 92: A circular component with a slot.
- 93: A circular component with a slot.
- 42: A circular component with a slot.
- 63: A circular component with a slot.
- 64: A circular component with a slot.
- 44: A circular component with a slot.
- 115: A rectangular component with a slot.
- 123: A rectangular component with a slot.
- 116: A rectangular component with a slot.
- 125: A circular component with a slot.
- 124: A circular component with a slot.
- 121: A circular component with a slot.
- 55: A circular component with a slot.
- 53: A circular component with a slot.
- 54: A circular component with a slot.
- 56: A circular component with a slot.
- 57: A circular component with a slot.
- 58: A circular component with a slot.
- 43: A circular component with a slot.
- 36: A circular component with a slot.
- 59: A circular component with a slot.
- 34: A circular component with a slot.
- 60: A circular component with a slot.
- 1: A small rectangular component at the bottom right.
- 107: A small rectangular component at the bottom.

JAMES H. LAWSON, OF VINCENNES, INDIANA.

PRINTING AND ADDRESSING MACHINE.

Application filed April 14, 1925. Serial No. 23,034.

This invention relates to printing apparatus and has for its object the provision of a novel machine by means of which the name and address may be printed upon letters, newspaper wrappers, envelopes, post cards and the like prior or subsequent to the printing of the body, in the case of a letter or circular, the arrangement being such that the address will be automatically changed as each sheet, envelope or the like is fed through the machine.

An important object is the provision of a machine of this character embodying a mechanism for printing the body of a letter, circular or the like and further embodying the automatically changed address and salutation printing mechanism located in advance thereof, whereby the salutation and address may be printed and the body also printed at one operation or one passage of the sheet through the machine, thereby reducing the number of operations necessary in turning out the finished product.

A further object is to provide a printing mechanism in which the salutations and addresses may be carried by a continuous strip having a step by step movement operated synchronously with operation of the paper feed.

Another object is the provision of a machine of this type having separate feed mechanisms for sheets and envelopes, the separate feeds having individually operable drive mechanisms capable of being thrown selectively into or out of operation.

A further object is to provide a printing machine in which the body of a letter or circular is printed by means of a rotatable drum device and the salutation and address printed by means of a translationally movable member shifted step by step and adapted to have flat contact with the sheet, envelope or the like.

Still another object is to provide a novel transmission mechanism for the laterally travelling step by step actuated salutation and address printing device, this mechanism including means for permitting necessary slippage of the winding roll as the diameter thereof varies, means being also provided for effecting rewinding at the end of a series.

A still further object is the provision of a drive mechanism including a main shaft carrying cam devices and other drive elements for carrying the paper, envelopes or

the like through the salutation and address printing means and delivering them to the rotatable drum whereby in the case of letters or circulars the body thereof may be printed and whereby in both instances the rotary drum will act to kick out the paper or envelopes.

An additional object is to provide an addressing and printing machine in which the arrangement is such that a sheet, envelope or the like may be located at any desired position preparatory to addressing, the location of the parts being such that the operator may see each new address, salutation or title before it is printed, thereby facilitating the making of changes and corrections.

Another object is to provide a machine which may print, a letterhead, return address on an envelope, post office permit on a newspaper wrapper, or other similar or equivalent matter in addition to the address, title, salutation or the like, or instead thereof, there being naturally no limitations as to the character of the matter.

Yet another object is to provide a machine for this purpose having a compact construction and provided with a simply and peculiarly arranged drive and transmission machine embodying different mechanical elements all of which coact to give the proper timing for the successive operations, thereby avoiding likelihood of misprints and other defects, it being moreover a feature that the machine embodies structural details which will insure ease of adjustment, efficiency in action, accuracy in the work and durability in service.

To the attainment of the foregoing and other objects and advantages the invention preferably consists in the construction and arrangement of parts to be hereinafter more fully described and claimed, and illustrated in the accompanying drawings in which:

Figure 1 is a side elevation of the machine with certain housings in section to disclose the step by step mechanism for moving the stencil strip.

Figure 2 is an elevation of the opposite side,

Figure 3 is a front elevation,

Figure 4 is a fragmentary longitudinal section showing the paper feed means at the moment before a sheet starts feeding,

Figure 5 is a similar view showing a sheet as moved partly into the mechanism,

Figure 6 is a similar view showing a sheet as having been moved into engagement by the gripping rollers,

Figure 7 is a longitudinal section taken through the rear portion of the machine from a point somewhat in advance of the gripping rollers and showing the sheet as moved into position for the printing of the address, salutation or other matter,

Figure 8 is a view similar to Figure 7 showing the parts in position for printing the salutation and the like,

Figure 9 is a somewhat similar view showing the printing bed depressed and the stencil inker elevated,

Figure 10 is a view similar to Figure 9 showing the position of the parts when the paper has been moved to the printing drum,

Figure 11 is a fragmentary cross section showing the drive mechanism for the stencil reels and also illustrating the stencil inking means,

Figure 12 is a longitudinal section showing the portion of the mechanism used in printing envelopes, the envelope magazine being shown in place and the envelope feed being represented as at the backward limit of its stroke,

Figure 13 is a view similar to Figure 12 showing the feed member engaging an envelope,

Figure 14 is a similar view showing the parts in a different position and with the envelope as having been passed through the printing mechanism.

Referring more particularly to the drawings, the numeral 1 designates the frame of the entire machine, which frame may be of any necessary size and of any desired or convenient shape and materials. Secured to and rising from the rear portion of the frame are brackets 2 which journally support the printing drum 3 which may be of a construction similar to that used on the "Neostyle" machine, or the well known "Multigraph" machine, there being no particular limitations as to this detail. The purpose of the drum 3 is to effect printing of the body of a letter, circular or the like or to print post office permits and in fact any other desired matter upon newspaper wrappers or the like. Any desired printing means may be carried by this drum such as type or a stencil and it is also true that the inking means might consist of a ribbon, external swab or some means within the drum for permitting ink to pass through a stencil in case the latter is used in lieu of type.

Mounted at the forward end of the frame, by any suitable means, is a feed table 4 upon which may be laid a stack of sheets of paper indicated at 5.

Suitably journaled across the frame is a shaft 6 having any desired means thereon

whereby power may be applied for the purpose of driving all the mechanism to be described, though for the sake of illustration I have shown a simple crank handle 7 intended to be moved in the direction of the arrow in Figure 2. The shaft 6 carries a pinion 8 meshing with a pinion 9 on a shaft 10 on which is mounted a pinion 11 in turn meshing with a gear 12 on a shaft 13 suitably journaled in the frame. The shaft 10 carries a gripping roller 14 which coacts with a similar roller 15 carried by a shaft 16 located vertically beneath the shaft 10. The rollers 14 and 15 have their peripheries covered with rubber or the like indicated at 17 whereby they will be capable of gripping a sheet of paper, envelope or the like for moving it along when they are rotated. Though only the roller 14 is driven positively it will be seen that the roller 15 will be driven by virtue of its coaction therewith.

The paper feeding means comprises a pair of arms 18 rockably mounted on a shaft 19 and carrying a shaft 20 on which is mounted a roller 21 adapted to rest upon the stack of paper sheets 5. The pivoting of these arms 18 permits the roller 21 to rest upon stacks of different thicknesses, the roller and arms of course moving downwardly as the paper sheets are successively fed off the stack into the machine. A portion of the periphery of the roller 21 is recessed and let into the recess is a strip 22 of rubber or other similar material which will frictionally engage the topmost paper sheet and move it rearwardly into the printing mechanism to be described. The shaft 20 carries a pinion 23 meshing with an idle pinion 24 which in turn engages a second idle pinion 25 meshing with a pinion 26 on the shaft 13. Obviously, when the crank handle 7 is turned the pinions 8 and 9 will cause rotation of the gear 12 and shaft 13, the rotation of the latter being communicated through the pinions 25, 24 and 23 to the shaft 20 carrying the roller 21.

I also provide a pair of arms 27 carrying a roller 28 and pivotally connected at 29 with ears 30 on the arms 18. These arms 27 have depending portions 31 carrying rollers 32 located in the path of travel of and engageable by cams 33 on the shaft 13. As the shaft 13 is turned it is obvious that during a portion of its rotation the cams 33 thereon engaging the rollers 32 will lift the arms 18 carrying the roller 28 out of engagement with the stack of paper. It will be observed that the rotation of the roller 21 will cause the strip 22 to engage the topmost sheet in the stack and drag it rearwardly until it may engage beneath the roller 28, the paper buckling as indicated by the dot and dash lines in Figure 5. By the time that the paper sheet comes beneath this guide roller the cams 33 have moved into such position

that the arms 27 are lifted, of course carrying the roller 28. The rear end of the paper then passes beneath the roller 28 and finds its way to the coating rollers 14 and 15 and as the roller 14 is positively driven by turning movement of the crank 7, the paper will be pulled through the rollers 14 and 15 as shown in Figure 7 and will engage against a stop device to be described which will prevent further movement until the desired printing has been accomplished.

The brackets 2 carry horizontally disposed bearings 34 through which are journaled shafts 35 and 36 on which are mounted spools 37 and 38 carrying a strip 39 which has stencilled thereon the names and addresses of persons to whom circulars, letters, newspapers or the like are to be sent, the stencils being cut in any desired or preferred manner, the detail thereof not affecting the present invention. Initially the strip is wound entirely upon the spool 37 and is unwound therefrom and onto the spool 38 during the actuation of the machine. The strip passes under a suitable guide roller 40 located at one side of the frame 1. Throughout its length the stencil strip has both edges formed with perforations 41 which engage upon a sprocket 42 carried by a shaft 43 suitably journaled at the opposite side of the frame 1. The relative positions of the roller 40 and sprocket 42 are well illustrated in Figure 3.

In order that the sprocket 42 may be driven at periodic intervals for moving the stencil strip step by step for bringing the successive addresses 44 thereon into printing position, I provide a shaft 46 suitably journaled into the frame 1 and equipped with a sprocket 47 about which is trained a chain 48 in turn engaged with a sprocket 49 on the shaft 13. The shaft 46 is equipped with pins 50 projecting laterally therefrom and adapted to engage within radial slots 51 in a species of star wheel 52 carried by a shaft 53 on which is also mounted a spiral gear 54. The shaft 43 carries a small spiral gear 55 meshing with the spiral gear 54 so that as the crank handle 7 is turned to rotate the above described paper feeding mechanism the sprocket 42 will be rotated at periodic intervals through the instrumentality of the sprockets 49 and 47, chain 48, star wheel mechanism and spiral gears so that as each successive paper sheet is brought into printing position the successive addresses 44 on the stencil strip will likewise be brought into printing position with respect to the corresponding paper sheets.

The shaft 36 carrying the spool 38 also carries a pulley 56 about which is engaged a belt 57 trained about a pulley 58 on the shaft 43 so that as the stencil strip is unwound from the spool 37 the spool 38 will be turned to wind the strip thereonto. The

belt 57 and pulleys 56 and 58 will insure the necessary rotation of the spool 38 to take up the strip so that the strip will be kept taut. Owing to the fact that the belt may slip it is evident that differences in the diameter of the roll of tape on the spool 38 are properly compensated for.

In order that the strip may be rewound onto the spool 37 for starting a new series, I provide a shaft 59 carrying a crank handle 60 and having a clutchable connection with the shaft 35 so that the crank handle may be pushed in and turned to rewind the tape. I have shown a pair of guide rollers 61 in engagement with the tape where it engages upon the sprocket 42, the purpose being to prevent sagging of the tape and disengagement of the perforations therein from the teeth of the sprocket 42.

Thus far, I have given a description of the construction and operation of the paper feeding means and the means for moving the stencil strip step by step into position to bring the successive stencils carrying the addresses, salutations or the like in position over the successive sheets. The printing mechanism used in connection with the stencil strip comprises a suitable frame structure 62 slidably mounted on guides 63 which are arranged vertically at opposite sides of the path of the stencil strip and which are suitably secured to the frame 1. The frame 62 is held normally in elevated or non-printing position by coil springs 64 encircling the guides 63 and bearing against the underside of the frame 62 and against stop collars, lugs or the like 65 on the guides. This frame is provided with one or more downward extensions 66, one being probably sufficient, with which extension is pivotally connected at 67 a link 68 in turn pivotally connected at 69 with an arm 70 pivoted on a shaft 71 suitably mounted in the frame 1. A roller 72 is journaled on an intermediate portion of the arm 70 and coacts with a cam 73 carried by the shaft 46. The shape of the cam 73 is such that it will move the arm 70 downwardly at periodic intervals for moving the frame 62 downwardly preparatory to printing. The springs 64 provide the means for subsequently moving the printing frame upwardly and for maintaining the roller 72 in engagement with the periphery of the cam 73.

As stated above there is provided stop means for limiting movement of the paper 5 under the influence of the feed rollers 14 and 15. I have shown this stop means as consisting of an upstanding lug-like element 74 carried by an arm 75 pivoted at 76. The arm 75 carries a roller 77 coacting with a cam 78 on the shaft 46 so that at periodic intervals during the rotation of this cam the stop 74 will be retracted from engagement with the edge of the paper sheet so that the

120

125

130

paper sheet may pass onto the printing drum 3. Of course the movement of the parts is so timed that the stop 74 remains up until after the salutation and other similar matter are printed. The numeral 79 indicates a coil-spring which is connected with the arm 75 for holding the roller 77 in engagement with the cam 78 at all times.

The supporting plate or top 4 is provided with an opening 80 at a point beneath the stencil strip and located beneath this opening but adapted to be projected upwardly therethrough is a bed plate 81 carried by a bracket 82 slidable on one of the guides 63. Pivoted on a transverse shaft element 83 is an arm 84 having its free end carrying a roller 85 engaging against the periphery of a cam 86 on the shaft 46 so that as this cam rotates the arm 84 will be moved up and down at periodic intervals. Pivoted on this arm at an intermediate point is a roller 87 bearing against the underside of the bed plate 81 and acting to move the latter up and down at intervals.

Mounted in the frame 62 are forward and rear channel shaped guide strips 88 within which the edges of the stencil strip 44 are slidably engaged, the purpose being not only to control the horizontal position of the 30 stencil strip with respect to the top plate 4 and paper sheets 5 but also to strengthen and hold the edges of the stencil strip and prevent buckling or other distortion thereof when the inking mechanism is brought into 35 play.

The opposite ends of the frame 62 are provided with upwardly inclined guide members 89 having elongated slots 90 therein. Slidably mounted within these slots are carriages 91 urged downwardly by coil springs 92. These carriages are provided with bracket extensions 93 within which are journaled trunnions 94 on the ends of a roller 95. This roller is the ink container and is 45 provided with a filling opening 96 normally closed by a plug or cap 97. Carried by the roller 95 is a roller 98 of absorbent or permeable material which is saturated with ink by flow thereof through a plurality of 50 perforations 99 in the roller 95.

Suitably journaled on the main frame to the rear of the above described printing mechanism is a roller 100 provided for the purpose of conducting the paper, after 55 printing by the stencil strip, to the printing drum 3. While, as above stated, the printing drum may be operated in any desired manner, I have in the present instance shown its shaft 101 as carrying a gear 102 60 meshing with a gear 103 in turn driven by a gear 104 meshing with a gear 105 on the shaft 46. Any suitable housing 106 may be provided for enclosing all of these gears together with the sprockets 47 and 49 and

chain 48 trained thereabout, the advantages of the housing being quite obvious.

In the operation, assuming that a paper sheet 5 has been fed by the means above described and has reached a position with its edge engaging the stop 74, it will be seen that the timing of the parts is such that one of the stencils will be in printing position above the sheet. At such a time the ink roller is elevated as is also the frame 62 carrying the inking mechanism and the guides 88 through 70

which extends the stencil strip. The bed plate 81 is in lowered position with its top surface flush with the top surface of the plate 4. The position of the paper sheet and these other parts is well illustrated in 80 Figure 7. When the shaft 46 rotates, by the above described driving mechanism operated by the crank handle 7 or its equivalent, the cam 73 engaging the roller 72 will swing the arm 70 downwardly so that the link 68 connected with the extension 66 will pull the entire printing frame 62 downwardly to bring the stencil strip 44 into contact with the paper sheet. At the same time, the cooperation of the cam 86 with the roller 85 will 90 swing the arm 84 upwardly so that the roller 87 thereon engaging the bed plate 81 will move the latter upwardly through the opening 80 and into engagement with the underside of the paper sheet 5. The bed plate 81 95 remains in this position for an appreciable period and as it approaches its uppermost position the paper is brought into engagement with the permeable roller 98. As pressure comes against this roller its carrying 100 brackets 91 move rearwardly or upwardly along the guide slots 90, the roller consequently moving longitudinally of the machine and giving a rolling pressure on the top surface of the stencil strip. Obviously 105 ink from this permeable roller will pass through the stencil cuttings and make the desired impression on the paper sheet.

After the printing operation has been effected, as above described, the rotation of the 110 shaft 46 carrying the cams 73, 78 and 86 will cause the arm 84 to move downwardly so that the bed plate will be retracted out of engagement with the paper sheet. At the same time the high point of the cam 73 has moved past the roller 72 so as to permit the springs 64 to return the printing frame to its uppermost and inactive position. At or about this same time the cam movement permits the arm 75 to move downwardly, retracting the stop 74 and permitting the paper which has by this time buckled into the position shown by dot and dash lines in Figure 8 to pass beneath the roller 100 so as to be caught beneath and be printed upon by 120 the rotary drum 3. This retracted position of the various parts is well illustrated in Figure 9. The printing operation by the 125

- drum is a conventional one and need not be illustrated in detail. There is preferably provided a deflector or guard plate 107 adjacent the drum for the purpose of preventing the paper sheet from adhering thereto so that as the sheet passes beneath the drum it will also pass beneath this plate and be kicked off into any suitable receptacle or stacking device if one be provided.
- 10 One of the important features of the machine is its ability to print the names and addresses on the successive ones of a stack of envelopes, and in order to permit this work to be done, I have provided an envelope printing attachment which necessarily involves a different feed mechanism from that above described for feeding sheets of paper to the printing mechanism. In carrying out this feature I provide an upstanding casing 110 of suitable size to fit the particular size of envelopes to be fed. The above described feed roller 14 must be removed to accommodate this envelope holder which is located at the position shown in Figures 12, 13 and 14 with its forward portion over the roller 15. The envelopes, indicated at 111 are stacked within the casing 110 with their flaps 112 underneath and extending toward the printing mechanism.
- 20 The envelope feeding means includes a suitable guide structure 113 located beneath the top plate 4 of the machine, along which guide structure is slidably mounted a rack device 114 in engagement with a segmental gear 115 carried by a shaft 116 journaled transversely of the main frame 1 at a point below the above mentioned shafts. The shaft 116 also carries a segmental gear 117 meshing with a segmental gear 118 pivoted on a shaft 119 suitably mounted in the frame 1. The gear 118 is actuated by means of a cam 120 on the shaft 46, this cam engaging a roller 121 journaled on the segmental gear 118. A suitable coil or other spring 122 is provided for urging the segmental gear 118 upwardly so that its roller 121 will be in constant engagement with its actuating cam 120. A coil spring 123 may be provided connected with the segmental gear 115 for normally urging it in one direction so that the rack 114 will be returned to its forward or normal position after each rearward stroke thereof as effected by the segmental gear 115.
- 30 As the cam 120 is fixed on the shaft 46 it is obvious that the segmental gear 118, the segmental gear 117 and the shaft 116 will be moved when the machine is used for printing paper sheets instead of envelopes.
- 40 However, it is intended that the envelope feeding mechanism be entirely inactive when paper sheets are being printed and for this reason I provide a releasable driving connection between the shaft 116 and the segmental gear 115 so that the latter may remain stationary notwithstanding the movement of the associated parts. While this releasable connection might be of any mechanical construction preferred, I have, for purposes of illustration, shown a retractable pin or key 124 for locking the hub of the gear 115 to the shaft 116. This pin is adapted to be held in its operative or coupling position by means of a pivoted arm 125 engageable within a peripheral groove 75 in the pin.
- 50 Pivoted within the rack member 114, which is of hollow formation, is a finger 126 having an extension 127 with which is connected a coil spring 128 which acts to urge the finger upwardly. The top plate 4 of the machine is provided with an elongated slot 129 which permits passage of the finger during the feeding action of the envelopes. However, when this rack 114 is at the forward limit of its movement or in non-feeding position, the finger 126 will engage against the underside of the top plate 4 at a point in advance of the slot 129 and be held down against the resistance of the spring 90 128, as shown in Figure 12.
- 60 In the operation of the envelope feeding mechanism, it is obvious that when the pin 124 is in its active or coupling position the segmental gear 115 will be moved back and forth, moving the rack 114 correspondingly. Assuming that the envelopes are in place, and that the rack 114 is at the forward limit of its movement, as shown in Figure 12, when the rack starts rearwardly the finger 126 will pass beyond the end of the slot 129 and be projected, by the spring 128, therethrough so as to engage above the flap of the lowermost envelope. The rear wall of the casing 110 has its lower end provided with an outlet slot 130 through which the lowermost envelope will be dragged by the finger as the rack 114 moves rearwardly of the machine. The actual feeding position of the finger is shown in Figure 13. When the envelope 100 reaches the proper position the above described stencil printing mechanism comes into play and at the same time an arcuate shoe 131 on the shaft 46 reaches such a position that it engages against the underside 103 of the envelope. The instant that printing ceases, the feed rack 114 moves forwardly while the shoe 131 turns rearwardly and kicks out the envelope.
- 70 From the foregoing description and a 110 study of the drawings it will be apparent that I have thus provided an automatic addressing, salutation and body printing machine in which the changes in the addresses on successive sheets of paper, wrappers, envelopes and the like are made automatically and without any attention on the part of the operator. It will be noted that each stencil when in printing position is in plain view so that mistakes may be corrected.

and so that an undesired address may be omitted, this latter operation being effected by moving the stencil strip manually. In case of a spoiled sheet or envelope, the 5 stencil strip may be manually moved back to its prior position and a second impression or printing made. Ample provision has been made for all contingencies which may ordinarily arise in the matter of 10 adjustments, corrections, variations in the size of paper stock, and the like. As all the cam mechanism is carried by a single shaft it is obvious that many of the essential working elements are concentrated and so related 15 that it will be impossible for the machine to get out of order especially as there is no relative movement of the operating cams. In fact the number of parts has been kept down to the minimum so that there will be no 20 likelihood of derangement.

While I have shown and described a preferred embodiment of the invention, the right is reserved to make all such changes in the form, construction and arrangement 25 of parts as will not depart from the spirit of the invention or the scope of the subjoined claims.

Having thus described the invention, I claim:

30 1. In a machine of the character described, a table, spools located at opposite sides thereof, a stencil strip wound upon one spool and adapted for movement transversely of the table to be wound upon the 35 other spool, means for feeding paper and envelopes along the table beneath the stencil, an inking roller adapted to press upon the top of the stencil, means for moving the inking roller downwardly into engagement 40 with the stencil, and means for moving said inking roller synchronously with the paper and envelope feeding means.

2. In a machine of the character described, a table, means thereon for printing 45 the body of a letter, and address and salutation printing means including a stencil strip mounted in advance of said body printing means, means for feeding paper or envelopes along the table beneath the stencil strip, 50 means for holding paper or envelopes temporarily stationary beneath the stencil means, and an inking roller mounted above the stencil strip and operating synchronously with said feeding means.

55 3. In a machine of the character described, a table, a stencil strip, means for printing the body of a letter, means located in advance of said means for printing the address and salutation, comprising means 60 for moving said stencil strip laterally of said table step by step, an inking roller above said strip, a movable bed member, means for moving paper or envelopes along the table beneath said stencil strip, and means for 65 simultaneously moving the inking roller

downwardly and the bed member upwardly synchronously with said paper or envelope moving means.

4. In a machine of the character described, a table, spools located at opposite 70 sides thereof, a stencil strip wound upon one spool, movable transversely of the table and adapted to be wound onto the other spool, means for feeding paper and envelopes along the table beneath the stencil, 75 the table having an opening, a bed plate beneath the opening, an inking roller above the stencil, and means for simultaneously moving the bed plate upwardly through the opening and the inking roller downwardly 80 into engagement with the stencil.

5. In a machine of the character described, a table, printing means thereon for printing the body of a letter, and address and salutation printing means including a 85 stencil strip mounted in advance of said body printing means, means for feeding paper and envelopes along the table and beneath the stencil, stop means for holding the paper and envelopes in printing position 90 beneath the stencil, printing means above the stencil, means operating synchronously with the paper and envelope feeding means for moving said second-named printing means downwardly, and means for subsequently releasing said stop means. 95

6. In a machine of the character described, a table, body printing means thereon, address and salutation printing means located in advance of said body printing means including spools rotatably mounted at opposite sides of the table in upright position, a stencil strip initially carried by one spool and adapted to be wound onto the other, means for rotating said other spool 100 while permitting slippage thereof, means for moving the stencil strip step by step including toothed drive elements engaging perforations in the strip, a constantly rotating driving element, and a star wheel transmission interposed between said driving element and said toothed elements. 105

7. In a machine of the character described, a table, body printing means thereon, address and salutation printing means located in advance of said body printing means including spools rotatably mounted at opposite sides of the table in upright position, a stencil strip initially carried by one spool and adapted to be wound onto the other, means for rotating said other spool while permitting slippage thereof, means for moving the stencil strip step by step including toothed elements engaging perforations in the strip, gear mechanism for driving the toothed elements, a star wheel for driving said gear mechanism, and a constantly driven rotary member having a tap-pet cooperating with the star wheel. 115 120 125

8. In a machine of the character de- 130

scribed, a table, body printing means thereon, address and salutation printing means located in advance of said body printing means including spools rotatably mounted

- 5 at opposite sides of the table in upright position, a stencil strip initially carried by one spool and adapted to be wound onto the other, means for rotating said other spool while permitting slippage thereof, means for 10 moving the stencil strip step by step, and manually operable means connected with said first-named spool for effecting rotation thereof.

9. In a machine of the character described, 15 a table, a step by step movable stencil strip arranged transversely of the table, means for moving the strip, a frame slidably mounted above the table, an inking roller slidably and rotatably mounted in said frame, and means 20 for simultaneously moving the frame downwardly to bring the said roller into engagement with the stencil, and means for moving the roller transversely of the stencil.

10. In a machine of the character described, 25 a table, a step by step movable stencil strip arranged transversely of the table, means for moving the strip, a frame slidably mounted above the table, an inking roller slidably and rotatably mounted in said frame, means for simultaneously moving the frame downwardly to bring said roller into engagement with the stencil, means for moving the roller transversely of the stencil, said last-named means including inclined 30 guides in the frame, carriages slidable in the guides and constituting bearings for the inking roller, and yieldable means in the guides permitting movement of the carriages therealong when the roller presses upon the 35 stencil.

11. In a machine of the character described, a table, feed means for moving paper sheets along the table, body printing means at one end of the table, address printing means in advance of the body printing means, the address printing means including a stencil strip arranged transversely of and movable step by step across the table, stop means for stopping movement of the paper 45 sheet when it reaches printing position beneath the stencil, means for bringing the paper into engagement with the stencil, means above the stencil for applying ink thereto, and means for releasing the stop means to permit the feeding means to move the paper sheet to the body printing means.

12. In a machine of the character described, a table, feed means for moving paper sheets along the table, body printing means at one end of the table, address printing means in advance of the body printing means, the address printing means including a stencil strip arranged transversely of and movable step by step across the table, stop 50 means for stopping movement of the paper 55

sheet when it reaches printing position beneath the stencil, means for bringing the paper into engagement with the stencil, means above the stencil for applying ink thereto, and means for releasing the stop means to 70 permit the feeding means to move the paper sheet to the body printing means, all of said means being cam actuated.

13. In a machine of the character described, a table, feed means for moving paper sheets along the table, body printing means at one end of the table, address printing means in advance of the body printing means, the address printing means including a stencil strip arranged transversely of and 75 movable step by step across the table, stop means for stopping movement of the paper sheet when it reaches printing position beneath the stencil, means for bringing the paper into engagement with the stencil, means above the stencil for applying ink thereto, means for releasing the stop means to 80 permit the feeding means to move the paper sheet to the body printing means, and a single drive means for synchronously actuating all of said means.

14. In a machine of the character described, a table, a step by step movable stencil strip device extending transversely of the table, paper feeding means, a paper stop, a vertically movable frame carrying an inking roller above the stencil strip, a bed plate beneath the stencil strip, means for moving the bed plate upwardly, means for simultaneously moving the frame downwardly into printing position, means for subsequently moving said stop into inactive position and moving the frame upwardly and bed plate downwardly.

15. In a machine of the character described embodying a printing mechanism and including a table, the table being adapted to support a stack of paper sheets, paper feeding means comprising arms pivotally mounted and carrying a roller resting upon the stack of sheets, the roller having an insert of elastic material adapted to frictionally engage the paper, means for rotating said roller, a pair of coating rollers located rearwardly of said first-named roller 110 and receiving the paper sheet between them, and means for simultaneously rotating all the rollers.

16. In a machine of the character described embodying a printing mechanism and including a table, the table being adapted to support a stack of paper sheets, paper feeding means comprising arms pivotally mounted and carrying a roller resting upon the stack of sheets, the roller having an insert of elastic material adapted to frictionally engage the paper, means for rotating said roller, a pair of coating rollers located rearwardly of said first-named roller and receiving the paper sheet between them, means 120 125 130

for simultaneously rotating all the rollers, arms pivoted on said first-named arms and carrying a guide roller located in advance of said pair of rollers, and cam actuated means 5 for moving said last-named arms and guide roller carried thereby up and down.

17. In a machine of the character described, printing means, a table, and envelope feeding means on the table comprising 10 a casing adapted to hold a stack of envelopes arranged with their flaps downwardly and extending toward the printing means, the table having a longitudinal slot, a reciprocating member mounted beneath the table, 15 means for moving said member, and a spring pressed finger within said member adapted to project through the slot into engagement above the flap of the lowermost envelope whereby to move the envelope through the 20 printing means upon movement of said member.

18. In a machine of the character described, printing means, a table, and envelope feeding means on the table comprising 25 a casing adapted to hold a stack of envelopes arranged with their flaps downwardly and extending toward the printing means, the table having a longitudinal slot, a reciprocating member mounted beneath the table, 30 means for moving said member, a spring pressed finger within said member adapted to project through the slot into engagement above the flap of the lowermost envelope whereby to move the envelope through the 35 printing means upon movement of said member, said reciprocating member being formed as a rack, and a driven segmental gear meshing with the rack.

19. In a machine of the character described, printing means, a table, and envelope feeding means on the table comprising 40 a casing adapted to hold a stack of envelopes arranged with their flaps downwardly and extending toward the printing means, the table having a longitudinal slot, a reciprocating member mounted beneath the table, means for moving said member, a spring pressed finger within said member adapted to project through the slot into engagement above the flap of the lowermost envelope whereby to move the envelope through the printing means upon movement of said member, said reciprocating member being formed as a rack, a driven segmental gear meshing with the rack, a constantly rotating shaft 45 carrying the segmental gear, and releasable means for locking said segmental gear to its shaft.

lope feeding means on the table comprising a casing adapted to hold a stack of envelopes arranged with their flaps downwardly and extending toward the printing means, the table having a longitudinal slot, a reciprocating member mounted beneath the table, means for moving said member, a spring pressed finger within said member adapted to project through the slot into engagement above the flap of the lowermost envelope 50 whereby to move the envelope through the printing means upon movement of said member, said reciprocating member being formed as a rack, a driven segmental gear meshing with the rack for moving the same in one direction, and a spring connected with said segmental gear for moving it in the other direction.

20. In a machine of the character described, printing means, a table, and envelope feeding means on the table comprising 60 a casing adapted to hold a stack of envelopes arranged with their flaps downwardly and extending toward the printing means, the table having a longitudinal slot, a reciprocating member mounted beneath the table, means for moving said member, a spring pressed finger within said member adapted to project through the slot into engagement above the flap of the lowermost envelope 65 whereby to move the envelope through the printing means upon movement of said member, said reciprocating member being formed as a rack, a driven segmental gear meshing with the rack, a constantly rotating shaft 70 carrying the segmental gear, and releasable means for locking said segmental gear to its shaft.

In testimony whereof I affix my signature.
JAMES H. LAWSON.
